UNITED STATES PATENT OFFICE.

THOMAS J. RIDER, OF NEW YORK, N. Y., ASSIGNOR OF ONE HALF TO CORNELIUS H. DE LAMATER, GEORGE H. ROBINSON, AND WILLIAM DE LAMATER, ALL OF SAME PLACE.

HOT-AIR ENGINE.

SPECIFICATION forming part of Letters Patent No. 393,723, dated November 27, 1888.

Application filed December 22, 1887. Serial No. 258,670. (No model.)

To all whom it may concern:

Be it known that I, THOMAS J. RIDER, of the city and county of New York, and State of New York, have invented a new and useful Improvement in Hot-Air Engines, of which the following is a specification.

My invention relates to single-cylinder closed cycle hot-air engines—such, for example, as the Ericsson engine, shown and described in Letters Patent No. 226,052, dated March 30, 1880. In that engine there is a downward prolongation of the cylinder which constitutes the air heater, and in the cylinder and heater work a motor-piston and a transfer-piston. This transfer-piston is not tight within the cylinder or heater, and as it rises the air above it and between it and the power-piston is caused to pass downward between the transfer-piston and the wall of the cylinder to the heater, and is by the upward movement of such piston transferred from the cylinder downward to the heater. In the operation of such an engine the air passes downward in a thin film around the transfer-piston, and as it is thus held or maintained in such thin film directly in contact with the wall of the heater, the heat is very effectively applied to it. In such engine as heretofore made, however, the air as soon as it reaches the lower end of the transfer-piston escapes directly into the internal space of the heater, and as the piston rises it is obvious that the air is held in contact with the wall of the heater for a less and less period, and the point at which the air escapes from the confined space between the transfer-piston and the wall of the heater into the internal space of the heater gradually rises as the piston makes its ascent.

It is obvious that the heat is not so readily transmitted to the air when it is maintained in considerable volume within the heater-space as it is while the air is passing downward through the thin or confined space between the transfer-piston and the wall of the heater.

In order that in an air-engine of the kind above described the air in its transfer from above to below the transfer-piston may have during the whole stroke of the piston the

same length of travel over the heater-surface, 50 or, in other words, in order to provide for confining the air which passes downward in contact with the outer wall of the heater until it reaches the bottom of the heater at all times and during the whole length of stroke of the 55 piston, a sleeve or lining-piece has been applied within the heater.

My invention consists in the novel construction of this sleeve or lining-piece and its novel combination with the cylinder, the heater, 50 and the piston, as hereinafter described and claimed.

In the accompanying drawings, Figure 1 represents a vertical section of the Ericsson engine embodying my invention; and Fig. 2 65 is a plan of a lining-piece or sleeve which I introduce within the heater.

Similar letters of reference designate corresponding parts in both figures.

A designates the cylinder of the engine, 70 which is surrounded by a water-jacket, A', and B designates the heater which forms a downward prolongation of the cylinder proper A, and is represented as made separate from the cylinder and secured thereto by bolts a, 75 forming a flanged joint.

C designates the motor-piston which works within the cylinder A, and D designates the transfer-piston, whereby air which is above it and between it and the motor-piston C is by 80 the rising movement of the transfer-piston D caused to pass downward around the transfer-piston and into the heater B, where it receives fresh calorific. The connections through which the motor-piston C and the transfer-piston D 85 operate may be the same as in the Ericsson patent above referred to, and no special description of these parts is necessary. As clearly shown, the transfer-piston D does not fit tightly the cylinder A, and in these engines 90 as heretofore made the air above the transfer-piston as the transfer-piston rises is forced down the annular space surrounding the transfer-piston, and as soon as it reaches the bottom of the piston escapes into the internal space of 95 the heater B.

It is obvious that as the piston D rises, the point at which the air escapes from confine-

ment between its circumference and the wall of the heater rises correspondingly, and therefore as the piston rises the air has a gradually decreasing travel in direct contact with the 5 wall of the heater B.

To produce a uniform heating of the downwardly-flowing air during the entire upward stroke of the transfer-piston there is provided in the heater B the cylindrical lining-piece or sleeve E, which forms between the wall of the heater and the sleeve an annular space, e. At the upper end of this lining-piece or sleeve is an internal flange which fits snugly to and steadily guides the transfer-piston, and the said lining-piece is also furnished at its upper end with external lugs or projections, e', which fit within the heater B in such manner as to center the said sleeve or lining-piece in the heater and the cylinder A, but to leave 15 between the said lugs or projections a free passage for air at the upper end of such sleeve or lining-piece, as shown at e''. The said annular space e thus opens at its upper end, e'', directly to the annular space between the transfer-piston D and the wall of the cylinder A, and opens at its lower end at the point e' into the internal space of the heater. As the piston D rises the air is forced downward around it, and, entering the open top e'' of the annular 25 space e, flows down such annular space and is finally delivered at the open bottom e' thereof. As the piston D rises the lining-piece or sleeve remains stationary, and consequently it maintains the full and equal length of the annular 30 space e during the entire rising movement of the piston.

It will be observed that by providing the

lining-piece E with the internal flange, e', to fit the piston D the said lining-piece may be made large enough internally for the rest of 40 its length to be entirely clear from the said piston as air entering the said lining-piece at the bottom can do no harm provided it cannot pass between the piston and the upper end of said lining-piece. The lugs or projections 45 on the exterior of the lining-piece e' are received in the rabbet b in the upper end of the heater B, and are clamped in the joint between the heater and the cylinder A to hold the lining-piece in place.

What I claim as my invention, and desire to secure by Letters Patent, is—

1. The combination, with the cylinder, the air-heater, and the transfer-piston, of the lining-piece or sleeve provided with an internal flange around its upper end to fit the transfer-piston and centered relatively to the air-heater, substantially as herein described.

2. The combination, with the cylinder A, the heater B, made separate from and secured to the lower end of the cylinder, and the power and transfer pistons C D, of the lining-piece or sleeve E, having at the upper end laterally-projecting lugs or ears which are clamped in the joint between the cylinder and heater, 60 said lining piece or sleeve being fitted to the transfer-piston, and forming between it and the wall of the heater the annular air passage e, substantially as herein described.

THOMAS J. RIDER.
